UNITED STATES PATENT OFFICE.

WILLIAM H. FROST, OF SCHENECTADY, NEW YORK, ASSIGNOR TO GENERAL ELECTRIC COMPANY, A CORPORATION OF NEW YORK.

MAGNETO-DRIVE FOR INTERNAL-COMBUSTION ENGINES.

1,046,579.

Specification of Letters Patent. Patented Dec. 10, 1912.

Application filed September 13, 1911. Serial No. 649,086.

To all whom it may concern:

Be it known that I, WILLIAM H. FROST, a citizen of the United States, residing at Schenectady, county of Schenectady, State 5 of New York, have invented certain new and useful Improvements in Magneto-Drives for Internal-Combustion Engines, of which the following is a specification.

This invention relates to internal combustion engines, and especially to those in which a plurality of cylinders are arranged in two or more groups placed at an angle to each other. In one form of engine, for example, there may be eight cylinders arranged in two groups, four cylinders in each group, and the crank shaft may have four cranks, the connecting rods being so arranged that each pair of corresponding pistons can be coupled to the same crank.

Owing to the angular relation of the cylinders in each pair, the time of ignition in one will not coincide with that in the other. Provision must therefore be made for producing the ignition spark in the second cylinder in each pair, when the common crank has made a certain angular advance from the position it occupied when the spark was produced in the first cylinder of the pair. As the angular displacement of the two cylinders may be some odd number of degrees not evenly divisible into 360, it is evident that the problem is not an easy one when reliance is placed upon only one source of igniting current, such as a magneto.

Various attempts have been made to overcome the difficulties and complications of this situation, and my invention aims to simplify and at the same time solve the trouble. Moreover the construction which I have devised enables me to sufficiently accelerate the armature in the field magnets of the magneto or magnetos so as to produce a good spark at the proper time to start an engine, thus overcoming the difficulty of sufficiently accelerating the magneto armature by the rotation of the shaft of an engine by hand. This feature is applicable to engines of any type, whether single 45 or multiple cylinder. In order to accomplish these results, I mount the magneto in

such a manner that it can be shifted bodily in an arc concentric with the driving gear.

I am aware that it has been proposed to rock the field magnet of a magneto angularly about the axis of the armature shaft in order to advance or retard the spark, but this is a different proposition from the one herein set forth, whereby the entire magneto is shifted bodily from one angular 60 position to another around the periphery of its driving gear. This means that the armature is rotated in the magneto field during its lateral movement of revolution with the magneto around said gear. This 65 rotation of the armature induces a spark at the point of the maximum induction, if the motion is sufficiently rapid, so that a charge in a cylinder can be exploded.

When the engine has more than one cylinder or group of cylinders, I employ separate magnetos, one for each group of cylinders, each with its armature so set with relation to its field magnets that the point of maximum induction occurs at the proper 70 instant for that particular group of cylinders. The magnetos are geared to the same driving gear so that they always maintain the same difference in times of sparking. They are mounted in such a manner as to 75 be capable of angular adjustment concentric with the driving gear in order that the sparks may be advanced or retarded simultaneously and to the same extent in the groups of cylinders by shifting said magnetos bodily in one direction or the other, and this construction also permits the production 80 sparks for starting the groups of cylinders in proper sequence, by rocking the magnetos simultaneously. 90

In the accompanying drawings, Figure 1 is an end elevation of a portion of a multi-cylinder internal combustion engine embodying my invention. Fig. 2 is a diagrammatic view showing the relative arrangement of the cylinders, cranks, gears, etc., and Fig. 3 is a side elevation of the parts shown in Fig. 1. 95

In the engine illustrated, the cylinders 1 and 2 stand with their axes at an angle of 100 45 degrees, and each cylinder is one of a group of four, standing in the same plane,

each cylinder in one group being opposite a corresponding cylinder in the other group. The connecting rods 3 and 4 of each such pair of opposite cylinders are coupled to a common crank 5 on the engine shaft. A pinion 6 is secured on said shaft, and meshes with a gear 7 on the cam shaft. Another gear 8 on the cam shaft meshes with the two pinions 9 and 10 on the shafts of the two magnetos 11 and 12. These machines may be of any desired make and are preferably mounted side by side on a bracket 13 which has a hub 14 secured upon a short shaft 15, which is journaled in a frame 16 and in axial alignment with the cam shaft. The frame is secured to the end plate 17 of the engine. Suitable mechanism is provided for angularly adjusting said bracket in an arc concentric with the gear 8. This may consist of a lever 18 on a rock shaft journaled in a bracket 19 secured to the end plate 17, and having an arm 20 connected by a link 21 with an arm 22 on the shaft 15 carrying the bracket 13. The lever 18 has a latch operated by a button 23 and engaging notches 24 in a stationary quadrant 25 to enable said lever to be locked in any desired position after the bracket has been angularly adjusted. It will be readily understood that by swinging the lever up or down, the bracket will be rocked to and fro, and the position of the two magnetos will be shifted with reference to the gear 8 so as to advance or retard the spark in accordance with the direction in which the bracket is moved. As each magneto is set to give a spark for its own group of cylinders, and both magnetos give their sparks at the same point in the stroke of the pistons they serve, it follows that both sparks will be advanced or retarded to the same extent. It will also be readily understood that by rocking the magnetos rapidly, sparks can be produced for starting without the necessity of turning over the engine fast enough to produce such sparks in the ordinary way.

While I have described the invention as applied to a multicylinder engine having two groups of four cylinders each, yet it is evidently applicable to an engine having any number of cylinders arranged in any number of groups and set at any angle or angles to each other. In practice, however, it has been found of especial value in eight cylinder engines, as described and shown.

In accordance with the provisions of the patent statutes, I have described the principle of operation of my invention together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. The combination with an internal combustion engine having two or more cylinders arranged in planes at an angle and acting on a common shaft, of igniting magnetos each serving the cylinder or cylinders in one plane only, and means for simultaneously advancing and retarding the sparks produced by said magnetos. 75

2. The combination with an internal combustion engine having two or more cylinders arranged in planes at an angle, and acting on a common crank shaft, of igniting magnetos each serving the cylinder or cylinders in one plane only, said magnetos being geared to a common actuating gear. 80

3. The combination with an internal combustion engine having two or more cylinders arranged in planes at an angle, and acting on a common crank shaft, of igniting magnetos each serving the cylinder or cylinders in one plane only, said magnetos being geared to a common actuating gear, and means for shifting said magnetos simultaneously in an arc concentric with said gear. 85

4. The combination with an internal combustion engine having two or more cylinders arranged in planes at an angle, and acting on a common crank shaft, of igniting magnetos each serving the cylinder or cylinders in one plane only, said magnetos being geared to a common actuating gear, and a bracket supporting said magnetos and mounted to rotate on the axis of said gear. 95

5. The combination with an internal combustion engine having two or more cylinders arranged in planes at an angle, and acting on a common crank shaft, of igniting magnetos each serving the cylinder or cylinders in one plane only, said magnetos being geared to a common actuating gear, a frame secured to said engine, and a bracket supporting said magnetos and mounted on said frame to rotate on the axis of said gear. 105

6. The combination with an internal combustion engine having two or more cylinders arranged in planes at an angle, and acting on a common crank shaft, of igniting magnetos each serving the cylinder or cylinders in one plane only, said magnetos being geared to a common actuating gear, a frame secured to said engine, a bracket supporting said magnetos and mounted on said frame to rotate on the axis of said gear, and a lever pivoted on said engine and connected with said bracket. 115

7. The combination with an internal combustion engine having two or more cylinders arranged in planes at an angle, and acting on a common crank shaft, of igniting magnetos each serving the cylinder or cylinders in one plane only, said magnetos being geared to a common actuating gear, a frame secured to said engine, a bracket supporting 125

said magnetos and mounted on said frame to rotate on the axis of said gear, a lever pivoted on said engine and connected with said bracket, and a latch and notched quadrant for locking said lever.

8. The combination with an internal combustion engine, of an igniting magneto having a pinion on its armature shaft, a driving gear meshing with said pinion and actu-

ated by said engine, and means for permitting an angular movement of the entire magneto with reference to said driving gear.

In witness whereof, I have hereunto set my hand this 11th day of September 1911.

WILLIAM H. FROST.
